RETORT

Ernest Leslie Schultz, East Melbourne, Victoria,
AustraliaApplication March 22, 1929, Serial No. 349,175,
and in Australia November 22, 1928

8 Claims. (Cl. 202—104)

This invention relates to a retort for the destructive distillation of carbonaceous material such as coal, shale, lignite and other organic substances and has been devised to provide a retort of great utility wherein the organic materials are passed in a thin film from the top of the retort to the bottom in the direction opposite to the heat, and further with, the use of a retort as hereinbefore described a maximum result is obtained through the factors of a reasonable amount of material fed continuously, high efficiency and safety in operation, a positive force feed and discharge, the total elimination of dust in the distillate which obviates clogging, the prevention of the adherence of carbon to the retort shell, and high efficiency in the application of heat, all form essential features embodied in the invention.

An object of the invention is to provide a retort immune from any defects of expansion or contraction, the working of the retort being thus unimpaired, while the elimination of dust allows of the continuous working.

A further object of the invention is to construct a retort wherein the material in its passage through the retort is subjected to a positive continual motion in the manner of a screw, the motion of the material preventing the carbonized material from adhering to the retort heating shell at the same time confining the material to the heating space around said shell and, preventing it from being forced out, as the constant steady movement of the material through the heating space and discharge has a scraping effect and by feeding the material in a thin film through the retort in the manner of a spiral or screw, a maximum area is presented and period of treatment is effected in the retort.

A retort in accordance with this invention is characterized by a refractory center with a central passage therein leading from a burner to the stack, the retort center having passages leading therefrom to form a circumferential space between the said center and a cylinder surrounding it, the central passage of the refractory center incorporating a valve, to control the heat from the burner, an intermediate member being disposed around the said refractory center comprising upper and lower cylinders which move in seals the intermediate member being supported by spaced bars between the upper and lower cylinders which also support a tier of overlapping inverted truncated coil shells, while means are provided in the retort for rotating said shells and means also for imparting an intermittent and limited vertical motion to the shells, which have

fitted thereon a screw or spiral edge, an outer cylinder being disposed externally of the shells with gas pipes emanating therefrom into seals in which the outer cylinders and gas pipes rotate.

A feature of the invention comprises the provision of a tier of overlapping truncated conical shells rotating within the heating space of the retort, and being adapted to intermittently operate in a vertical direction, the shells having a spiral edge or worm thereon extending towards the inner heating cylinder of the retort whereby the material being treated is forced down and around the said heating space in a spiral path around the inner heating cylinder to rotary means for continuously discharging the residue.

A further feature of the invention consists in that the tier of overlapping inverted truncated conical shells are continuously rotated and also intermittently raised and lowered around an inner heating cylinder and within an outer rotating casing, the upper and lower cylinders supporting the said shells being provided with seals while the outer casing has emanating therefrom gas pipes also provided with seals within which the said casing and pipes rotate.

One form of retort for carrying the principal method and essential features above described into practical effect will now be described with reference to the accompanying drawings in which:—

Figure 1a is a vertical cross sectional view of the top portion of the retort,

Figure 1b is a vertical cross sectional view of the bottom portion of the retort,

Figure 2 is a plan view,

Figure 3 is a vertical cross sectional view of a detail, and

Figure 4 is a side view of a detail.

According to this invention the retort 5 is constructed of fire brick or refractory material as at 6 with spaced external projecting portions as at 7 from the bottom to the top to allow of the passage of the heating gases from an oil burner 8 or fire box 9 disposed below the same and over an inner fixed steel cylinder 10 which is formed around the refractory center 6 and above the fire brick is domed to a narrow diameter, the narrower tube or chimney stack 11 extending upwardly to connect the building frame 12 to afford the necessary support at the upper end.

The refractory center 6 of the fire brick has a central passage 13 with cross passes 14 near the top to lead the combustible gases to the heating cylinder 10 at one or more points to obtain the lighter fractions and this central passage is

controlled to the extent of its opening by a valve 15 having a spindle 16 extending through the upper tube or stack 11 where it is connected to a lifting lever 17, the valve 15 allowing of the feeding of a greater or lesser quantity heat to the top portion of the combustible heating space around the inner cylinder 10 according to the material being treated.

The chimney stack 11 is fitted with an asbestos lining 18 on the outside and this lining is surrounded by the fixed inlet feed tube 19 from a bunker 20 disposed above the lever thereof, so that the material is fed by gravity to an enclosed space 21 around the dome 20 above the centre of the retort.

This enclosed space is formed by an upper enclosed extension 22 of an intermediate framing and is formed with an internal ring 22a entering a seal 22b formed around the inlet tube 19. This intermediate framing is composed of spaced vertical angle bars 23 forming supports for the tier of overlapping inverted truncated conical shells 24 hereinafter described, the portion below the said shells 24 being in the form of a cylinder 25 and extends into a rotating circular trough 26 near the bottom of the retort and below the level of the lowest gas pipe.

Between this lower cylinder 25 and the inner fixed cylinder 10 a space 27 for the residue or spent material is provided below the overlapping shells 24, and this cylinder 25 is formed with a spiral feeder 28 for the spent material which is delivered to the trough 26 in which liquid is also filled while the bottom cylindrical fixed member 29 for the retort 5 which supports the inner shell 10 is also provided with an extension ring 30 in a fixed liquid seal 31.

The angle iron bars 23 are thus fastened to the upper and lower cylindrical members 22, 25 of the retort and on the inside extending diagonally in a downward and inward direction, so that they overlap each other, is a tier of truncated conical shells 24 suspended in the heating space 32, the said shells being fitted to the spaced vertical angle beams.

These truncated conical shells 24 overlap each other as illustrated to allow of expansion and contraction and each shell extends downwardly at an angle towards the inner heating cylinder 10 of the retort 5, each shell 24 overlapping the next lower shell 24 and leaving a narrow gas space therebetween, the overlap being of sufficient length to prevent the material being forced back through the openings 33 thus formed.

As above described the roof 22c of the upper cylinder 22 of the inner fixed cylinder 10 is formed with a downturned flange or ring 22a at the centre and is received in a seal 22b formed in a circular trough 22d at the bottom of the bunker feeding chute 19, the trough 22d being returned upwardly within the roof 22c above the bottom level of the flange or ring 22a above-mentioned.

Externally of the overlapping shells 24 and their supporting bars or beams 23 is a gas space 32 substantially thin, receiving the gases from the material in their various fractions and this gas space is enclosed by an outer steel cylinder 34.

The intermediate upper and lower cylinders 22, 25 which support the angle bars or beams 23 carrying the truncated conical overlapping shells 24 are supported by a platform 35 supported on a plurality of rollers 36 in bearings 37 which are supported on the H iron beams 38.

The outer cylinder 34 which may be externally

lined with asbestos and the intermediate frame carrying the overlapping shells 24 and bars 23 are given rotary motion and the total rotary weight is carried by the flanged rollers 36 supported on the H iron frame 38.

The platform 35 with the outer cylinder 34 and the top and bottom cylinders 22, 25 supporting the angle bars or beams 23 carrying the spaced overlapping conical shells 24 are rotated while externally of the inner metal fixed cylinder 10 of the retort 5 and carried by the inner edges of the overlapping shells 24 to which it is bolted is a screw or spiral worm edge 39 or other scraper which extends from the top to the bottom of the length of the tier of overlapping inverted truncated conical shells 24.

In order to increase the efficiency of the retort and ensure the movement of the material continuously through the heating space, additionally to the rotary motion, an intermittent and limited vertical motion is imparted to the overlapping shells 24 to give the material a shaking or jarring motion to prevent the material adhering to the inner fixed cylinder 10 at any point of contact on its path to the discharge.

One means for imparting the intermittent motion to the overlapping shells consists in fitting to or forming on the underside of the platform 35 a plurality of spaced fixed cams 35b in the path of the rollers 36 with the gradually rising surface 35c of each cam leading to the rollers so that on the rollers 36 passing the end 35d of the cams, the whole platform and consequently the overlapping shells 24 drop suddenly and then have a gradual rise and then a sudden drop to provide the shaking or jarring motion to the material, the rack surfaces 54 being of sufficient depth to allow of this movement while still remaining in gear with the pinions 51 of the drive, and in order to limit the upward movement of the platform 115 overlapping shells 24 and other parts supported thereby, rollers 36a are suspended from a frame 36b a short distance above the platform 35, this being necessary as if the material clogs, the back pressure would force the rotating parts upwardly, 120 particularly if the rotating mechanism is held up for any reason.

It is preferred that the worm edges on the overlapping shells 24 be not arranged in line, but are stepped as illustrated in Figure 3 so that after 125 each drop it bights in a new place and so continually grips a new surface of the material to assist the passage thereof.

At points around the circumference of the outer cylinder 34 are seals 40 into which respectively lead gas pipes 41 extending from the cylinder 34 for the gas from the gas space 32 and these gas pipes 41 receive from slots 42 in the shell and rotate in the water seals 40 while a pipe or pipes 43 extend into the hood above the liquid level and then to a closed shallow depth seal 44 through which it bubbles and from which it is then led to an exhauster 45 or exhausters so that the distillates can be further treated by fractional distillation, the closed seal also having a take-off 140 pipe 46 to an oil tank (not shown).

The seals 40 are provided with overflow pipes 47 as illustrated.

The outer cylinder 34 (and by it the intermediate upper and lower cylinders 22 and 25 supporting the angle bars 23 and the overlapping shells 24) is rotated preferably by a worm gear 48 driving a vertical shaft 49 in turn at each end driving a pinion 50 gearing with a pinion 51 supported in bearings 52 mounted to the beams 150

53, the latter pinions 51 gearing with spaced circular racks 54 fitted to the outer shell 34.

As above described the lower rotating cylinder 25 below the tier of overlapping shells 24 leads 5 the spent material or residue into a seal 26 forming an element of the rotating discharge means.

This seal 26 is supported on a circular band or rollers 55 mounted on spindles 56 in bearings 57 fitted to the member 29 of the retort 5 and the 10 seal 26 has an outwardly extending rim 58 fitted with a rack 59 gearing with a pinion 60 on a horizontal shaft 61 mounted in bearings 62 and carrying fast and loose pulleys 63, 64, the shaft being driven from any suitable source of power.

15 On one side of the retort a scraper 65 which may be formed in the manner of a stationary plough share extends into the discharge seal 26, the share guiding the material into a chute 66 leading to a truck 67 preferably on rails 68 for 20 easy handling, thus providing for the automatic and continuous discharge of the residue or spent material.

In operation, the material is fed from the bunker 20 to the receiving space 21 from whence it is 25 forced in a film from the top to the bottom of the heating space 69 in which the tier of overlapping truncated conical shells 24 operate and combined with the spiral worm edge 39 bolted thereto and along the length of the tier of shells allows of 30 a slow continuous screwing, forcing and scraping of the material through the heating space to the discharge as above described, so preventing the carbon and deleterious matter produced in the 35 gasification of the material from adhering to the inner heating cylinder 10 of the retort by scraping the cylinder walls 10 in the constant steady movement of the treated material through the heating space and discharge, the feeding of the 40 material through the heating space and the discharge of the spent material being continuous and automatic as above described.

If desired, the overlapping shells 24 need not be fitted with the screw 39 or other form of scraper, the weight of the material being sufficient to 45 force itself towards the discharge end.

Pyrometer rings 72 are provided around the circumference of the retort 5 enabling the registration of the temperature, the rings being spaced from each other and held by insulation to the 50 rotating shell, the pyrometer element 69a working in the material.

Two lead wires 70, 71 from the element 69a connect the rings 72 and two collector brushes 73, 74, one on each ring, extend to the instrument so that on rotation the temperature is continuously recorded.

I desire it to be understood that various improvements and modifications may be embodied without departing from the spirit and scope of 60 the invention, the method, functions and essential features of which are above described.

What I claim as my invention and desire to secure by Letters Patent is:—

1. A vertical retort comprising a heating cylinder located within said retort and positioned vertically, two superposed vertical cylinders spaced from each other surrounding said heating cylinder and spaced horizontally therefrom and concentric therewith and mounted for rotation on their axes, a member between said heating cylinder and said superposed vertical cylinders and surrounding and spaced horizontally from said heating cylinder and attached to the upper of said superposed vertical cylinders, a tier of overlapping inverted truncated conical shells spaced from

each other and surrounding said heating cylinder and having their axes vertical between said heating cylinder and said member and spaced horizontally from said heating cylinder and concentric with said heating cylinder, said shells being attached to said member, means for intermittently vertically raising and lowering said shells, an annular trough concentric with said heating cylinder and surrounding one of said superposed vertical cylinders, an annular projection upon each of said superposed vertical cylinders concentric therewith and said trough for providing means for sealing the space between the two superposed cylinders from the atmosphere, means for conveying gas from the space 90 between the conical shells and said superposed vertical cylinders through the space between the two superposed cylinders, and means for rotating said superposed vertical cylinders upon a vertical axis and thereby rotating said shells. 95

2. A vertical retort comprising a hollow retort center of refractory material having a vertical central passage from a burner to a stack, passages leading from the retort center forming a circumferential space between the retort center and a cylinder surrounding the same, a valve for controlling the heat from the burner, a member comprising two superposed vertical cylinders spaced from each other surrounding said cylinder and spaced horizontally therefrom and concentric therewith, a plurality of spaced bars between the upper and lower cylinders for supporting said member, a tier of overlapping, inverted, truncated conical shells spaced from each other and having their axes vertical between said cylinder and said member and spaced from said cylinder and said member and concentric with said cylinder, said shells being attached to said member, means for intermittently raising and lowering said shells, an annular trough surrounding 105 on of the superposed cylinders, an annular projection on each of said superposed cylinders concentric therewith and extending into said trough for providing means for sealing the space between the superposed cylinders from the atmosphere, 110 means for conveying gas from the space between the conical shells and the said member through the space between the two superposed cylinders, means for rotating said member on its axis and thereby rotating said shells and means for continuously discharging the solid residue from the 115 retort at the lower part thereof.

3. A vertical retort comprising a vertical heating cylinder positioned within said retort, a member also positioned within said retort and surrounding said heating cylinder, a tier of overlapping inverted truncated conical shells spaced from each other and surrounding said heating cylinder and spaced horizontally therefrom and carried by said member, means for intermittently moving 120 said shells in a vertical direction, means for rotating said member upon a vertical axis and thereby rotating said shells, an outer rotary cylinder mounted for rotation on its axis and surrounding said member and said shells, an annular 125 trough surrounding said outer rotary cylinder, gas off-take means upon said rotary cylinder for conveying gas through the same extending into said trough for sealing the gas take-off from the atmosphere, means for passage of gas from the 130 space between the heating cylinder and the shells to said off-take means and a spiral edge provided upon said shells extending towards said heating cylinder of the retort to aid in the feeding of solid material through said retort.

135

140

145

150

4. A vertical retort comprising a vertical heating cylinder for said retort located within said retort, a member positioned within said retort surrounding said heating cylinder, a tier of overlapping inverted truncated conical shells spaced from each other and surrounding said heating cylinder and spaced therefrom and carried by said member, means for intermittently moving said shells in a vertical direction, means for rotating said member upon a vertical axis and thereby rotating said shells, an outer rotary cylinder mounted for rotation on its axis and surrounding said shells and said member, means for passage of gas from the space between said shells and said heating cylinder to the outside of said retort, a spiral edge upon said shells extending towards said heating cylinder, discharging means located at the base of said retort for discharging solid material from the same and a screw 20 for feeding solid material from the base of said shells into said discharging means.

5. A vertical retort comprising a vertical heating cylinder located within said retort, a member also located within said retort and surrounding said heating cylinder, a tier of overlapping inverted truncated conical shells spaced from one another and surrounding said heating cylinder and spaced therefrom and carried by said member, means for reciprocating said shells in a vertical direction, a spiral edge upon said shells for directing the material passing through said retort against said heating cylinder, means for rotating said member and thereby rotating said shells in order to convey the material in a spiral passage around said heating cylinder and a spiral guide upon said member below said tier for discharging solid residue from said retort.

6. A vertical retort comprising a vertical heating cylinder located within said retort, a member surrounding said heating cylinder and also located within said retort, a tier of overlapping inverted truncated conical shells carried by said member and spaced from each other and surrounding said heating cylinder and spaced therefrom, means for rotating said member upon a vertical axis and thereby rotating said shells, a platform fixed to said member for supporting said member, fixed cams upon said platform, supporting rollers for said platform mounted for traversing said fixed cams, said cams being ar-

ranged to produce a gradual rise and sudden drop alternately of said member and the shells carried thereby when said member is rotated and means for limiting the upward movement of said shells.

7. A vertical retort comprising a fixed vertical heating cylinder located within said retort, a vertical outer cylinder surrounding said heating cylinder and spaced therefrom, means for rotating said outer cylinder on its vertical axis, a member located within said retort between said heating cylinder and said outer cylinder and spaced from said heating cylinder and said outer cylinder, a tier of overlapping inverted truncated conical shells spaced from each other and surrounding said heating cylinder and spaced therefrom and carried by said member, said shells being suspended in the annular space between said heating cylinder and said outer cylinder, means for reciprocating said shells vertically, said member being connected to said outer cylinder so that upon rotation of said outer cylinder said member and the shells carried thereby will also be rotated, a spiral edge formed upon said shells to grip material passing through the retort upon each reciprocation of the shells in order to direct the solid material against the surface of said heating cylinder and means for continuously discharging solid material from the retort at a lower portion thereof.

8. A vertical retort comprising a fixed vertical heating cylinder located within said retort, a member also positioned within said retort and surrounding said fixed heating cylinder, a tier of overlapping inverted truncated conical shells spaced from each other and mounted upon said member between said member and said heating cylinder, said shells surrounding said heating cylinder and being spaced therefrom, a vertical outer rotary cylinder surrounding said member and fixed thereto and mounted for rotation on its axis, means for reciprocating said shells in a vertical direction, means for rotating said rotary cylinder and thereby said member upon a vertical axis and thereby rotating said shells and a spiral edge upon said shells for feeding solid material in the retort in a spiral manner around said heating cylinder.
